UNITED STATES PATENT OFFICE

2,037,946

RADIO RECEIVER

Joseph Stüsser, New Britain, Conn.

Application December 26, 1933, Serial No. 703,972

1 Claim. (Cl. 250—14)

This invention relates to new and useful improvements in radio receiving, and has for its principal object to provide a device which will make it possible to listen in on radio broadcast or police calls etc. in any place without having to hook up an antenna or ground connection or separate earphones, because by contact with the hand the human body is utilized as an antenna. At the same time this device is of such small physical dimensions, that it may be conveniently carried around and also used as a flashlight.

The invention consists in certain novel features of construction which can be readily understood by reference to the description of the drawings and to the claim hereinafter given.

Of the drawings: Figure 1 represents a sectional view of the flash light radio receiver embodying the features of the present invention.

Figure 2 represents a development of the ring plates of the regeneration control condenser.

Figure 3 represents the schematic diagram of the electrical circuit.

In the views of the drawings 1 represents the hand contact coil utilizing the human body as antenna. 2 represents the insulating tube which carries the hand contact coil. 3 is the tin foil serving as antenna condenser in combination with tubes 2 and 4. Condenser tuning tube 5 is threaded and screws into the threaded housing tube 6, on the outside of which is mounted the insulating tubes 2 and 4 and coil 1. Tubes 5 and 6 are made of conductive metal. Inside of tube 5 is mounted one side of the tuning condenser unit, which consists of round metal tubes 7. These tubes 7 are made to such sizes, that when placed into each other, sufficient space is left for the tubes 8 of the other side of the tuning condenser to interpose and thereby forming a condenser with the air space as dielectric. The number of tubes depends on the capacity which is required. The innermost of the tubes 7 acts also as shield for the vacuum tube 9.

A socket 10 is fixed to the top cover of housing tube 6 in such a manner that vacuum tube 9 can be inserted or removed after condenser tuning tube 5 has been unscrewed. Inside of housing tube 6 a coil form socket 11 is fastened, which carries coil form 12 and also tubes 8 of the tuning condenser. The tuning coil 13 is wound on coil form 12. On top of socket 10 the grid leak 14 and grid condenser 15 are fastened. The extension tube 16 has extension 17 of battery casing 18, inserted into it. By removing extension 17 with casing 18, the wiring is made accessible. Casing 18 is filled with suffi-

cient batteries or pen light cells to supply the plate potential for vacuum tube 9. On top of casing 18 a small variable resistor 19 is mounted. Cover 20 of casing 18 is removable to make the batteries accessible. One end of casing 18 carries the earphone shell 21. Regeneration control condenser 22 consists of metal rings which have cutouts as shown in Figure 2. These cutouts can be brought in line and made to be opposite each other by turning the earphone cap 23, thereby increasing or decreasing capacity. One side of condenser 22 is mounted on the metal earphone shell 21. The other side of condenser 22 is carried by the earphone cap 23, which is made of insulating material and has an extension 10 to cover the condenser unit 22. The cells 24 for filament current supply of the vacuum tube 9 are housed in a conventional flash light unit, of which the bottom cover 25 is secured to the threaded condenser tuning tube 5. A contact button 26 protrudes through the wall 27 of the flash light unit, and makes contact with metal ring 28 on which a hinge 29 is mounted. The cable 30 consists of a conductor which is covered with strong insulating material, and therefore 15 can be used as a convenient handle for carrying the flash light radio unit. Hinge 31 is fastened to housing tube 6 and a wire is connected on this end of cable 30 to the filament terminal of tube socket 10, thereby conducting the positive 20 filament current to the vacuum tube 9. Cable 30 is the only wire connecting the lower adjustable 25 unit with the upper housing tube 6, which carries the antenna coil unit, tuning coil unit, vacuum tube 9, and one side of tuning condenser. 30 The negative filament current is conducted through tubes 5 and 6 by means of the contact 35 of the thread of these tubes. Switch 32 makes or breaks contact to supply current to the flash 40 light bulb 33.

The mode of operation of the flash light radio will now be summarized. To tune in on radio broadcasting, the listener places one hand around the contact coil 1, with the other hand turns on the filament current for vacuum tube 9 by means 45 of the variable resistor 19, and turns the flash light casing either left or right hand, thereby screwing or unscrewing tuning tube 5, which in turn increases or decreases capacity of the tuning condenser by increasing or decreasing 50 the amount of interposition of condenser tubes 7 and 8. The signal finally is adjusted to the desired level by turning earphone cap 23 of the regeneration control condenser 22.

Having described my invention, what I claim 55

as new, and desire to secure by Letters Patent, is:

5 A radio receiving device comprising an antenna system, said antenna system consisting of a hand-contact-coil with a fixed condenser in series, a tuning coil comprising a primary and a secondary winding, and a regeneration coil, said fixed condenser connecting one end of the contact coil to the low potential side of the primary winding of the tuning coil, the other end of the contact

coil being connected directly to the high potential side of the primary winding, and said contact coil being exposed to provide a surface for the hand of the listener to hold the radio receiving device and as a result of this contact utilizing the electrostatic capacity of the human body to balance the inductance of said regeneration coil. 5

JOSEPH STÜSSER.
